Patented Aug. 30, 1910.

UNITED STATES PATENT OFFICE.

CLARENCE I. ROBINSON, OF WEST NEW BRIGHTON, NEW YORK, ASSIGNOR TO STANDARD OIL COMPANY, OF BAYONNE, NEW JERSEY, A CORPORATION OF NEW JERSEY.

REFINING PETROLEUM.

968,692.

Specification of Letters Patent. Patented Aug. 30, 1910.

Application filed August 21, 1903. Serial No. 170,327.

To all whom it may concern:

Be it known that I, CLARENCE I. ROBINSON, a citizen of the United States, residing at West New Brighton, in the county of 5 Richmond and State of New York, have invented new and useful Improvements in Refining Petroleum, of which the following is a specification.

This invention relates more particularly 10 to the refining of such petroleum as is obtained from the oil fields in the State of Texas, near the town of Beaumont, in Jefferson county, the object of the refining being to obtain burning oil (kerosene). Said 15 petroleum is herein referred to as Beaumont oil, or Beaumont petroleum, for convenience of reference. These designations are each intended to include oil of the same or substantially similar character wherever found 20 or however obtained. They include petroleum distillates having such a character, as well as crude and other undistilled petroleum.

The ordinary method of refining petroleum 25 has heretofore been to distil the crude petroleum, and to collect by itself the fraction which distils over within the temperature limits of burning oil (kerosene), say, between about 250° F. and 600° F., more or 30 less; the precise points at which the collection of the burning oil (kerosene) distillate is begun and ended being varied according to the grade of oil desired; and when as much distillate proper for burning oil 35 (kerosene) has been collected as can be secured with ordinary distillation, it is a common practice to subject the residue to a species of destructive distillation termed cracking, by which is obtained a further 40 quantity of hydrocarbons with boiling points within the above mentioned temperature limits and capable of being used for burning oil (kerosene). The distillates from the two distillations (separately or in 45 admixture, according to the grade of oil to be made) are then treated by agitating the same with ordinary concentrated sulfuric acid (acid of 66° Baumé is commonly used for the purpose), allowing to settle, and 50 drawing off the acid sludge (which sinks), the oil (which remains in the agitator) being then washed with water repeatedly and afterward with an aqueous solution of alkali, in order to remove all acid bodies

from the oil. The so-treated oil constitutes 55 the ordinary commercial refined petroleum (otherwise burning oil or kerosene) of the United States, provided the petroleum refined is that from the Pennsylvania or the Lima, Ohio, oil fields, only in the case of the 60 Lima, Ohio, oil a special purification is resorted to, in order to eliminate the malodorous sulfur compounds peculiar to Lima oil.

If Beaumont oil is distilled, with or without cracking, and the burning oil distillate given the sulfuric acid treatment (as stated above), the resulting product, when burned in the ordinary petroleum (kerosene) lamps, will smoke badly; and this smokiness cannot be cured by treatment with sulfuric acid (66° B.), however large a proportion of such acid may be employed. I have discovered that it can be cured by the aid of sulfuric acid containing about or above 98 75 per cent. sulfuric monohydrate (H_2SO_4), hereinafter referred to as 98% sulfuric acid, or more shortly as 98% acid. This acid, as I believe I am the first to discover, is capable of attacking smoky hydrocarbons of Beaumont oil not acted on by the ordinary concentrated acid of 66° B.; which latter ordinarily contains and for the purposes of this specification can be taken to contain from 92½% to 93% sulfuric monohydrate. When 80 the burning oil fraction is agitated with such 98% acid, the latter unites with the smoky hydrocarbons to form sulfo bodies which settle out in the sludge, after the agitation is over. 85

A non-smoking oil can be obtained by simply collecting the burning oil fraction in the customary manner and then subjecting it to sufficient 98% acid applied in successive portions until a non-smoking oil 95 is obtained after washing and neutralizing. But to do this requires an immoderate amount of acid (namely, about as large a volume of acid as of oil) and would be practically prohibitive at present prices of 100 burning oil and 98% acid, respectively.

I have discovered that a large saving in the 98% acid can be effected by separating the lighter from the heavier portion of the burning oil fraction of Beaumont oil and 105 subjecting the heavier portion thereof by itself to said 98% acid, the lighter portion being advantageously treated with ordinary

concentrated sulfuric acid and not with 98% acid. After such treatment, said lighter portion would best be distilled, a residue of treated oil being left in the still. Were 5 said lighter and heavier portions to be subjected together to the 98% acid, a material part of the acid used to produce a non-smoking product therefrom would be expended on smoky and non-smoking hydro- 10 carbons of a portion of the oil, which can (as just stated) advantageously be refined without it. Burning oil distillate from Beaumont petroleum as it is received from the condenser is attacked by 98% acid before 15 its content of smoky hydrocarbons becomes so great as to require a treatment with 98% acid. I have further discovered that an additional saving of 98% acid can be effected by collecting the heavier portion of 20 the distillate with reference to its capacity for treatment with a moderate amount of 98% acid (say, about two pounds, more or less, of such acid to each gallon of oil treated) and after subjecting the so collected 25 oil to said acid in such moderate amount distilling the so treated oil in such manner as to carry over the main portion thereof while leaving a residue of the same in the still. By such partial distillation the 30 amount of 98% acid can be reduced in much greater ratio than the yield of non-smoking oil is reduced by the residuum left in the still; and by combining such after treatment with the specified collection of the oil to be 35 treated, the major portion of the burning oil fraction can be rendered non-smoking by the aid of said moderate amount of acid. And it may not in all cases be necessary or expedient, in using this further discovery, to 40 apply the 98% solely to the heavier portion of the distillate; for if the presence in the treated oil of all or part of the lighter end of the burning oil fraction would not prevent 45 a satisfactory treatment of the same with a moderate amount of acid, the preliminary removal of said lighter portion could be dispensed with.

The points at which the different cuts (or 50 changes of distillate receivers) are to be made in any distillation can be ascertained by a preliminary assay. Hereinafter figures obtained in my experience will be given; but it will be understood that they are given by way of illustration and example, and not 55 as excluding a working with other figures.

The burning oil distillate can be obtained 60 from the crude oil with or without cracking; but most advantageously cracking is resorted to; in order to increase the yield; and, when cracking is employed, it is considered an advantage and special improvement to collect the burning oil light end (which does not require treatment with 98% acid) in two distillations, namely, first, that 65 in which the crude oil is distilled; and,

second, that in which the cracked oil distillate is redistilled for burning oil distillate. I, therefore, most advantageously (a) distil the crude oil with collection of the burning oil light end so long as it can be utilized without treatment with 98% acid; (b) continue the distillation as long as distillation can safely be carried on and to conduct it in the known or in any suitable way to provoke cracking, after the cracking temperature is reached, and collecting all the distillate without distinction; (c) distil the last mentioned distillate and collect apart the burning oil light end thereof so long as it can be utilized without treatment with 98% acid, and (d) continue the distillation, with collection of the heavier portion of the burning oil fraction so long as it can be satisfactorily treated for smokiness with a moderate amount of 98% acid. But, although the burning oil distillate, thus obtained without the light end, can be refined with a moderate amount of 98% acid, such amount is in excess of the small quantities of 66° B. acid customarily employed in the ordinary sulfuric acid treatment; and it, therefore, becomes a matter of so much the greater importance to obtain the requisite supply of 98% acid economically. As one means of effecting such economy I avail myself of sulfur in the petroleum to be refined as material for the production of 98% acid for the refining operation.

In a divisional application No. 363,712, filed March 21, 1907, as a continuation of this present application and made in consequence of official requirement of division, I have described and claimed improvements in utilizing Beaumont petroleum by which I convert the naturally present sulfur therein into sulfuric acid; while at the same time I obtain utilizable oils. Combinations of operations composing these improvements with other operations herein specified form part of the invention to be protected hereby.

Another means of which I avail myself, in order to obtain the necessary amount of 98% acid at a cost which admits of its profitable use, consists in converting again into 98% acid the sulfur in the acid sludges from treating Beaumont burning oil distillate with such acid. Most advantageously, the said sludge is heated to an appropriate temperature (say, from about 250° F. to about 600° F.), and the gas thereby evolved is subjected to oxidation for the conversion of sulfur dioxide into sulfuric acid. Before entering the sulfuric-acid-making apparatus (either lead chamber or contact apparatus, for example, as may be preferred) the gas is subjected to such preparatory operations as may be considered necessary or desirable. The product of the lead chambers is concentrated to 98% acid in any known or desired way; that from the contact appa- 130

ratus, if not obtained as 98% acid, is converted into the same in any known or desired way.

I have devised certain improvements in utilizing acid sludge from refining petroleum, hereinafter set forth, which I have described and claimed in my application No. 170,326 of even date herewith, and the combination of which with other operations for refining Beaumont petroleum is claimed herein.

In the preceding description, when reference has been made to the use of sulfuric acid of about or above 98% monohydrate (H_2SO_4), it will naturally have been understood that the residue, amounting to about 2% or less, is mainly (if not wholly) water. It is possible, however, to have a sulfuric acid of about or above 98% monohydrate (H_2SO_4) in which the residue of about 2% or less should be mainly (if not wholly) sulfuric anhydrid (SO_3), instead of water; and such acid would perform the functions of the water-holding 98% acid; although at the present time it would be dearer. This latter would be strictly a fuming acid; since it would contain sulfuric anhydrid; but the proportion of this would be so much less than in ordinary fuming acid (which contains about 10%, if not more, of sulfuric anhydrid) as materially to affect the cost; and, in view of the fact that I am, as I believe, the first to discover that monohydrated sulfuric acid will attack the smoky hydrocarbons of Beaumont petroleum and the first to suggest the application thereto of the weak fuming sulfuric acid aforesaid, I believe I am entitled to claim (as I do) the application as well of the fuming as of the non-fuming sulfuric acid of about or above 98% monohydrate; and both are included in the expression "98% acid." Moreover, the smoky hydrocarbons of Beaumont oil attacked by 98% acid and not by acid of 45 66° B. are attacked by fuming sulfuric acid containing less than about 98% monohydrate (herein referred to as "stronger fuming acid"), and also by sulfuric anhydrid itself (which is also to be understood as covered by the expression "stronger fuming acid"). More or less of the above described procedure is new and capable of useful application in connection with a treatment of Beaumont burning oil distillate with the stronger fuming acid. Such matters are included also in the invention. For example, by the preliminary separation of the burning oil light end from the rest of the burning oil fraction, I can avoid loss of the stronger fuming acid (as well as of good burning oil) which would result from treating the burning oil distillate as ordinarily collected with such acid, in consequence of the acid combining with non-smoking hydrocarbons. Also by separating from the rest

of the burning oil fraction the portion (consisting as I have discovered of more than half) which can be refined by a moderate amount of 98% sulfuric acid, I avoid another loss of the stronger fuming acid which would result from treating burning oil distillate as ordinarily collected with such acid; for the oil which can be refined by a moderate amount of 98% acid can be refined by a moderate amount of anhydrid or of fuming acid of less than about 98% monohydrate. In fact, I may use this fuming acid or the anhydrid in place of 98% acid in the assay to determine the portion of the burning oil which can be refined with either a moderate amount of 98% acid or a moderate amount of fuming acid of less than about 98% monohydrate or of the anhydrid. Again, by distilling oil after it has been treated with fuming acid of less than about 98% monohydrate or with the anhydrid, leaving a proper portion behind in the still, I can effect a material saving of the acid to be used as compared with that which would be necessary to treat the oil with a single distillation. The said fuming acid, also the anhydrid, as well as 98% acid, seems to effect a change in smoky hydrocarbons which, although it does not cause them to settle out with the acid nor to be removed by the subsequent washing, does cause them to stay in the still in the subsequent incomplete distillation. Still further, I can convert the sulfur in the Beaumont crude oil and in the acid sludge into 98% acid (whether fuming or aqueous) or into fuming acid of less than about 98% monohydrate, or into anhydrid, and can utilize said sulfur in any of these forms in refining Beaumont burning oil distillate. The obtained acid (or anhydrid) could be used or sold for any purpose to which it might be applicable; and, if desired, said sulfur could be converted into 66° B. acid or, in fact, into acid of any desired strength for sale or use, as might be preferred; only the utilization of said sulfur, after conversion into proper acid, for removing smoky hydrocarbons from Beaumont petroleum is itself an important part of the present invention, which includes the new improvements herein set forth as well severally as (any two or more) collectively.

There are smoky hydrocarbons which are attacked by fuming or anhydrous sulfuric acid and not by 98% acid (either aqueous or fuming); the former can be resorted to in place of or in addition to the 98% acid when considered necessary or desirable. It is not essential, although most advantageous, to obtain non-smoking oil directly by the described procedure, as the product could be subjected to further operations or could be mixed with non-smoking oil in such manner as to obtain a non-smoking mixture.

In the preceding description only Beaumont oil (as above defined) has been named as the petroleum to be operated upon in accordance with the invention. This has been done as well for simplicity of description, as because the treatment of Beaumont oil is especially claimed. But it is evident that there may be other petroleum analogous to Beaumont oil in possessing a smoky burning oil fraction amenable to treatment with 98%, fuming, or anhydrous sulfuric acid, with or without having sulfur so present in the oil as to be convertible into hydrogen sulfate on exposure to proper temperature (to wit, to about or below 500° F.). The improvements of the present invention extend to the treatment of petroleum analogous to Beaumont oil; that is to say, it would be within the invention to subject 20 to the above described operations for refining Beaumont oil or to any new and useful portion of said operations any petroleum possessing a smoky burning oil fraction amenable to the specified acid with or without recovery of the sulfur in the acid sludge obtained as by-product, and with or without utilization of sulfur in the oil.

In the preceding description, apart from the reference to its use in the prior state of 30 the art, ordinary concentrated sulfuric acid (herein shortly referred to as "66° B. acid") has been mentioned as a refining agent only in connection with the lighter end of the burning oil fraction, it being applied there-to prior to an incomplete distillation thereof. A certain amount of 66° B. acid (say, 6 to 8 lbs. of acid, more or less, to the barrel of oil) can, however, be applied to said heavier portion preliminary to a further treatment 40 of the same with other acid, and thereby a diminution be effected of the amount of such other acid necessary to a yield of given quantity and quality. The acid intermediate 66° B. and 98% acids (herein shortly referred to as "intermediate acid") can similarly be used, and, when so used, it can replace a still larger part of 98% acid, or of the stronger fuming acid, if this should be used. Moreover, if it should be desired 50 for any reason to obtain the best yield obtainable with avoidance of both 98% and stronger fuming acid, intermediate acid could be used as a basis to select a burning oil cut for treatment with a moderate amount of such intermediate acid, with or without 66° B. acid, and with or without a subsequent incomplete distillation in either case. These applications of 66° B. and intermediate acids are included in the invention, as is also the general application of intermediate acid to Beaumont or analogous petroleum.

The invention also consists in a new or improved oil which, in addition to: (a) 60 having a refractive index which is ten,

twenty, thirty, forty or more ten-thousandths less than that of oil of like boiling point obtained from Beaumont petroleum by the ordinary procedure of fractionally distilling with or without cracking and then treating the burning oil (kerosene) distillate with 66° B. sulfuric acid, and which index may be, and most advantageously is, sufficiently below 1.4600 for the oil to be non-smoking when burned in ordinary kerosene lamps; (b) possessing mobility proper for climbing a lamp wick; (c) distilling, mainly if not wholly, within the temperature limits of burning oil (kerosene), to wit, between about 250° F. and 600° F., more or less; (d) yielding between 400° F. and 550° F. on a test distillation within temperature intervals of 25° F. portions of distillate, of which most, if not all, are, respectively, of greater gravity by two, three, four, five or more degrees Baumé than the portions similarly yielded in the same temperature intervals by Pennsylvania petroleum and of which the portions distilling over between 400° F. and 500° F. may, and most advantageously do, average not lighter than 40° B., say, about 35° B., more or less, for a straight Beaumont product, is further distinguished in some one or more or all of the following particulars as hereinafter set forth, namely: (e) the oil exhibits in the portions distilling over in 25° F. intervals between 400° F. and 500° F. or 550° F. bromin-absorbing capacities which are on the average less by one, two, three, four or more per cent. than those of the portions distilling over in 25° F. intervals between 300° F. and 400° F.; (f) the bromin-absorbing capacities of the portions distilling over in 25° F. intervals between 400° F. and 500° F. or 550° F. average less than six per cent., say, about one per cent., more or less, for a straight Beaumont product; (g) the refractive indexes of the portions distilling over in 25° F. intervals between 400° F. and 500° F. or 550° F. average not more than 1.4620 (say, 1.4600) when the densities of the same portions average 35° B. with an allowance at the rate of plus 20 ten-thousandths for each degree below or minus 15 ten-thousandths for each degree above 35° B.; so that if the 400° F.-500° F. portions should average 34½° B. the refractive indexes should not average above 1.4630; or if the densities should average 36° B. the refractive indexes should not average above 1.4605; (h) the oil has in the portions distilling over in 25° F. intervals between 300° F. and 400° F. hydrocarbons that quickly reduce fuming to non-fuming sulfuric acid in amounts which on the average are larger than the amounts in the portions distilling over in 25° F. intervals between 400° F. and 500° F. or 550° F.; (i) the oil exhibits in all or part of the portions distilling over in 25° F. intervals between 130

300° F. and 400° F. characteristics of an oil which has been incompletely distilled after subjection to sulfuric acid; (k) the oil exhibits in all or part of the portions distilling over in 25° F. intervals between 400° F. and 500° F. or 550° F. characteristics of an oil which has been subjected to such sulfuric acid in general as attacks smoky hydrocarbons of Beaumont oil not attacked by acid of 66° B., with or without exhibiting also, according to the case, the characteristics of one subjected to 98% acid as above defined in particular; (l) the oil exhibits in all or part of the portions distilling over in 25° F. intervals between 400° F. and 500° F. or 550° F. characteristics of one given an incomplete distillation after subjection to 98% acid as above defined or to other such sulfuric acid as attacks smoky hydrocarbons of Beaumont oil not attacked by acid of 66° B.

Oil thus distinguished which is in whole or in part a product of Beaumont or analogous petroleum is more especially but not exclusively claimed; for it is intended to include petroleum or hydrocarbon oil in general of the specified properties, as well as products of Beaumont or analogous petroleum in particular. In some of the claims the average refractive index of the 400° F. to 500° F. portions is stated for oil where said portions average between about 34½° B. and 36° B., as not above 1.4610 for oil of 35° B. with allowance at the rate of plus forty or minus twenty ten-thousandths for each degree B. respectively, below or above 35° B. I have obtained such new or improved oil from Beaumont petroleum by the refining above described.

Any suitable apparatus can be used to carry on the processes of the present invention. A refining plant is hereinafter described which it is considered best to use.

The following is a description of what is considered the best mode of carrying the invention into effect, reference being had to the accompanying drawing which is a diagram of the before mentioned plant. In this description details are given with fullness and particularity by way of example and illustration, in order the better to enable those skilled in the art to make and use my invention, and the several portions thereof as set forth in the preceding more general description and in the hereinafter written claims; but it will, of course, be understood that modifications can be made, so long as the substance of any one or more of the hereinafter written claims is taken.

The crude Beaumont petroleum is supplied after the usual manner to the crude oil still *a* by a charging line *b*; and when the still has been filled to the desired level it is heated so as gradually to raise the temperature of the still's contents. The gas and vapors as they are formed by the heat

pass over to the condenser *c* wherein they are cooled to condense the oil vapors. The liquid of condensation flows into the distillate receiver *d*. The gas, including any uncondensed vapor, passes either by the line *e* to be burned as fuel or otherwise disposed of, or by the gas line *f* to be utilized in sulfuric acid making. While the temperature of the vapors as they leave the still *a* is below about 500° F., more or less, the gas from the condenser *c* consists of about or above 85% hydrogen sulfid (ordinarily, if not always) and is then delivered to gas line *f*. The temperature is raised to this degree more gradually than in ordinary distillation, being regulated with special reference to the production of hydrogen sulfid to the best advantage, and the distillate being allowed to take care of itself.

Should the hydrogen sulfid given off at any time below about 500° F. be found to be unsatisfactory in quantity or quality, it can be sent into line *e* as long as it may be so; but in my experience this change of gas line has not been found expedient until about 500° F. is reached. At about or above this degree the gas should be turned into the line *e*, so soon as the evolution of hydrogen sulfid fails in quantity or quality, the line *f* remaining closed during the rest of the run.

While the temperature is rising toward 500° F., the distillate collects in the receiver *d* until it becomes too smoky for utilization without removal of smoky hydrocarbons therefrom beyond what can be accomplished by treatment with 66° B. acid and redistillation. This has been found in my experience to be when the gravity of the distillate at the worm end (that is, before it enters the receiver *d*) is about 42° B., more or less, the temperature of the vapors escaping from the still *a* being about 400° F., more or less. The distillate then in the receiver is hereinafter referred to as the first burning oil cut. It belongs to the lighter end of the burning oil fraction. It amounts, in my experience, to from five to ten per cent. of the crude oil supplied to still *a*. The inlet of receiver *d* is then closed and that of receiver *g* is opened, so that the distillate from condenser *c* will flow into this latter receiver. This change of receiver has been effected, in my experience, before the yield of hydrogen sulfid becomes unsatisfactory; so that for a time after the change of receivers the heating of the still *a* is regulated with special reference to the evolution of hydrogen sulfid. Afterward the heat of still *a* is regulated (as customary) with special reference to the distillate to be obtained.

The distillation is carried on with cracking which commences (in my experience) when the temperature of the liquid oil in

the still *a* is about 600° F., more or less, the distillate in the two receivers *d* and *g* then amounting to about 40%, more or less, of the crude oil supplied to the said still *a*.
 5 The distillation is continued as long as it is safe to do so, say, till the distillate in said two receivers amounts to about 85% of said crude oil. The oil in receiver *g* is herein termed the cracked oil distillate; although
 10 a large percentage is composed of uncracked products.

It is customary to have a receiver into which the distillate can be turned whenever it becomes undesirable in quality, the result
 15 of something accidental; the receiver *h* is provided for such purpose. When necessary, its inlet can be opened, those of the receivers *d* and *g* being closed. Any one of the three receivers could be used for this purpose,
 20 the other two serving to collect the first burning oil cut and the cracked oil distillate, respectively.

After the completion of a run, the crude oil still *a* can be emptied through the tar line *j* or in any suitable way, preparatory to refilling with crude oil for a new run.

The cracked oil distillate from receiver *g* is delivered by pump *r*, through line *s*, into distillate still *k*, wherein it is distilled to
 30 separate the burning oil from the heavier fraction. The vapors pass over to the condenser *l*, where they are reduced to the liquid state, any uncondensed products escaping by the line *m*, to be used as fuel or as may
 35 be desired. The distillate is collected in the receiver *n* until it becomes too smoky to be used in burning oil without removal of the smoky hydrocarbons beyond what can be effected by treatment with 66° B. acid and
 40 redistillation. In my experience, this occurs when the oil from the worm end is about 42° B., the temperature of the vapors from the still *k* being about 420° F., more or less, and the distillate in receiver *n* being
 45 about eight per cent. of the crude oil supplied to still *a*. This portion of distillate is hereinafter referred to as the second burning oil cut. Like the first burning oil cut, it belongs to the lighter end of the burning
 50 oil fraction.

After it has been collected, the oil from condenser *l* is run into receiver *p*, so long as the distillate from the worm end can be made non-smoking by treatment with a
 55 moderate amount of 98% acid and distillation of the so-treated oil. In my experience, the distillate (hereinafter termed the third burning oil cut) can be thus collected in the receiver *p* until it amounts to about 30% of the crude oil supplied to the still *a*, the gravity of the oil at the worm end being about 31° B., more or less, and the temperature of the vapors escaping from the distillate still *k* being about 550° F., more or
 65 less. The residuum in the distillate still *k*

is then withdrawn through tar line *q*, leaving the still empty for another run. This next run may be made on another lot of cracked oil distillate from receiver *g*, or it may be a distillation after treatment with
 70 acid of one or other of the burning oil cuts or of a mixture of said cuts; for as shown the one still *k* serves for both distillations. It is to be understood, however, without further statement, that where one still, agitator or other vessel is shown, in practice
 75 as many of such vessels as desired can be used, and that it is not material to distil or to collect different oils, or to treat different oils with acid in the same vessels.

The first and second burning oil cuts are treated with ordinary concentrated acid either separately or mixed together, as may be preferred. They are delivered from their respective receivers *d* and *n* by the pump *r* through a branch of the oil line *s* to the agitator *t*. Here the oil is agitated as customary in the sulfuric acid treatment with acid of 66° B.; and, after settling and drawing off the acid sludge through pipe *u* into
 80 sludge tank *w*, the oil is washed repeatedly with water and then with a solution of caustic alkali. The water and alkaline solution can be removed (after proper settling in each case) through the draw-off *x*. In my
 85 experience, about ten pounds of 66° B. acid to a barrel of the distillate treated is sufficient. The treated oil is delivered by pump *y* through part of oil line *s* into distillate still *k* and is subjected to an incomplete distillation therein, that is to say, it is distilled so long as the oil from the worm end is satisfactory. According to my experience, the distillation may well be stopped when the oil from the worm end is between 39°
 90 B. and 40° B. The effect of the incomplete distillation, after the acid treatment, is to reduce the oil's content of sulfur, as well as its content of smoky hydrocarbons. The oil from condenser *l* during this distillation collects in the receiver *n*. The residuum in still *k*, amounting, in my experience, to between ten and twenty per cent. of the charge of said still *k*, is then run off through the tar line *q*, leaving the still *k* ready for the
 95 next run. The third burning oil cut is pumped from receiver *p* into agitator *t* and is there agitated with 98% acid in moderate amount for about an hour. In this time, according to my experience, the effect of the
 100 acid will be exhausted. The acid should be applied in two portions and may be in all about two pounds, more or less, of acid to each gallon of the oil treated, namely, of the third burning oil cut. The oil should have
 105 a temperature of about 90° F., more or less, at the beginning of the treatment. The acid sludge is drawn off into the tank *w*, and the treated oil is washed repeatedly with water and afterward with a solution of caustic
 110 alkali. The treated oil is then delivered by pump *y* through part of oil line *s* into distillate still *k* and is subjected to an incomplete distillation therein, that is to say, it is distilled so long as the oil from the worm end is satisfactory. According to my experience, the effect of the
 115 acid treatment is to reduce the oil's content of sulfur, as well as its content of smoky hydrocarbons. The oil from condenser *l* during this distillation collects in the receiver *n*. The residuum in still *k*, amounting, in my experience, to between ten and twenty per cent. of the charge of said still *k*, is then run off through the tar line *q*, leaving the still *k* ready for the
 120 next run. The third burning oil cut is pumped from receiver *p* into agitator *t* and is there agitated with 98% acid in moderate amount for about an hour. In this time, according to my experience, the effect of the acid will be exhausted. The acid should be applied in two portions and may be in all about two pounds, more or less, of acid to each gallon of the oil treated, namely, of the third burning oil cut. The oil should have
 125 a temperature of about 90° F., more or less, at the beginning of the treatment. The acid sludge is drawn off into the tank *w*, and the treated oil is washed repeatedly with water and afterward with a solution of caustic
 130 alkali. The treated oil is then delivered by pump *y* through part of oil line *s* into distillate still *k* and is subjected to an incomplete distillation therein, that is to say, it is distilled so long as the oil from the worm end is satisfactory. According to my experience, the effect of the acid treatment is to reduce the oil's content of sulfur, as well as its content of smoky hydrocarbons. The oil from condenser *l* during this distillation collects in the receiver *n*. The residuum in still *k*, amounting, in my experience, to between ten and twenty per cent. of the charge of said still *k*, is then run off through the tar line *q*, leaving the still *k* ready for the next run.

alkali as in the ordinary sulfuric acid treatment.

The treatment with 98% acid greatly improves the oil; but it will still contain an excess of smoky hydrocarbons, as well as acid compounds which would cause the lamp wick to be charred were the oil without further refining burned in a lamp. The treated oil is, therefore, delivered by pump 10 *y*, through oil line *s*, into distillate still *k* and subjected to an incomplete distillation, that is, a distillation so long as the collected distillate constituting the third burning oil cut, after mixture with the light ends (first 15 and second burning oil cuts) furnishes a product which as a whole shows either by burning in a lamp or by the refractometer the proper freedom from smoky hydrocarbons. According to my experience, the distillation would best not be continued after 20 the oil from the worm end reaches 29 $\frac{1}{2}$ ° B. or somewhat lighter (say, between 30° B. and 31° B.) if the still should be running slowly. The third burning oil cut is collected 25 in the receiver *p*, or in the receiver *n*, if desired. The residuum, amounting, in my experience, to about ten per cent., more or less, of the treated oil charged into the still *k*, will contain the worst (smokiest) 30 portions of the oil. It is run off by the tap line *q*.

By the preceding operations there will have been obtained one, two or three lots of oil, according to the collection in one, two or 35 three receivers of the distillates from the incomplete distillation of the three burning oil cuts. The refining of said distillates is finished by subjecting them, separately or two or more of them in admixture, to treatment 40 in the usual way with a small quantity of 66° B. acid in the agitator *t*; and the finished oil is thence run by line *z* into the tank 2, wherein the oil from different cuts can be mixed, if not already in admixture. 45 In my experience, Beaumont crude oil contains such a small percentage of light products that steam stilling is not necessary for low test burning oil (kerosene); but if it should be desired to increase the fire test, 50 the finished oil, or one or both the lighter burning oil cuts, may be steam stilled to bring the product to the desired test. According to my experience, it should suffice to steam still the finished oil from the second 55 burning oil cut. Either or both of the finished light ends could be mixed with the finished heavier portion and the whole steam stilled.

The hydrogen sulfid from the crude oil 60 still *a*, together with a small proportion of other aeriform fluid therein, is conveyed by the gas line *f* to a storage gasometer 3, from which it is supplied to the burner 4, wherein both it and other combustible substances 65 present are burned, the hydrogen sulfid

being converted thereby into sulfur dioxid and water. These may both be delivered through gas line 5 into the lead chamber 6 for making sulfuric acid. They could be delivered into a tower 7; but this is not considered desirable, in view of the large proportion of water vapor in admixture with the sulfur dioxid. The water could, however, be separated by condensation and the sulfur dioxid, being heated, could be sent 75 either into tower 7 or lead chamber 6. It could be sent into other sulfuric acid making apparatus.

The acid sludge from tank *w* is delivered through acid sludge line 8 by pump 9 into 80 the acid sludge still 10 until the latter is filled to the desired level (say, 200 barrels of acid sludge in a still of 500 barrels' capacity). The still is provided with a rotary stirrer 11, in order to check foaming. After 85 charging the still is heated so as to keep up a good delivery of sulfur dioxid, say, about 2,500 cubic feet, more or less, per hour.

The evolution of gas begins at about 220° F. (temperature of the liquid), and at about 90 600° F. should be practically complete, only coke remaining in the still.

The gas and vapors from still 10 (which may be of iron) are passed through the condenser 12 (which should have a lead worm), 95 in order to separate the small amount of oil vapors carried over with the sulfur dioxid. The sulfur dioxid then passes by gas line 13 to a storage gasometer 14, from which (after being heated) it is sent either into tower 100 7 or chamber 6, in order to be converted into sulfuric acid.

Toward the end of the operation, in removing the last portion of sulfur from the sludge, some hydrogen sulfid comes over. 105 To convert this into sulfur dioxid (and water) the gas may be passed through the burner 4 on its way to the lead chamber 6. As the gas from condenser 12 is cold throughout the operation, it should be 110 heated before it is admitted into tower 7 or chamber 6. This can be done by passing all the gas through a burner (as 4, for example) in which combustion yielding sulfur dioxid is going on. Such passage insures 115 also the combustion of any small quantities of hydrocarbons which may be present in the gas. All the sulfur dioxid from such burner would pass into the sulfuric-acid-making apparatus.

The oil from condenser 13 runs into the receiver 15. It and the coke (removed from the still 10 preparatory to the next run) can be used as fuel or otherwise disposed of.

The dilute sulfuric acid from the lead chamber 6 is carried by line 16 to an apparatus 17, where it is concentrated to 98% acid by heating or by adding sulfuric anhydrid or by the aid of both operations. It is delivered by acid line 18 to a storage tank 130

19 from which it passes by line 20 to the tank 21 from which it is delivered by pump 22 into the agitator *t* as above described. The acid of 66° B. can be obtained from another portion of the same dilute acid and be delivered in the same way to the said agitator.

The finished oil in tank 2 will: (a) have a refractive index which is less as herein above specified than that of oil of like boiling point obtained from Beaumont petroleum by the ordinary fractional distillation and treatment of distillate with 66° B. sulfuric acid, and which, according to my experience, should be about 1.4540, and, therefore, sufficiently below 1.4600 for the oil to be non-smoking without admixture of other oil with the Beaumont product; (b) possess mobility proper for climbing a lamp wick; (c) distil mainly, if not wholly, within the temperature limits of burning oil (kerosene); (d) yield between 400° F. and 550° F. on a test distillation within temperature intervals of 25° F. portions which are, respectively, of greater gravity as herein above specified than the portions similarly yielded in the same temperature intervals by Pennsylvania petroleum and which may, according to my experience, be such that the average of the portions distilling over between 400° F. and 500° F. is about 35° B., more or less; (e) exhibit in the portions distilling over in 25° F. intervals between 400° F. and 500° F. or 550° F. bromin-absorbing capacities which on the average are less as herein above specified (say, by about four per cent. or more) than those of the portions distilling over in 25° F. intervals between 300° F. and 400° F.; (f) exhibit in the portions distilling over in 25° F. intervals between 400° F. and 500° F. an average bromin-absorbing capacity of about one per cent., more or less; (g) exhibit in the same 400° F.—500° F. portions an average refractive index of about 1.4600, more or less; (h) have in the portions distilling over in 25° F. intervals between 300° F. and 400° F. amounts of hydrocarbons that quickly reduce fuming to non-fuming sulfuric acid, the average of which amounts is greater than those in the respective portions distilling over in 25° F. intervals between 400° F. and 500° F. or 550° F.; (i) exhibit in the portions which distil over in 25° F. intervals between 300° F. and 400° F. characteristics of an oil which has been incompletely distilled after subjection to sulfuric acid; (k) exhibit in the portions distilling over in 25° F. intervals between 400° F. and 500° F. or 550° F. characteristics of one which has been subjected to 98% sulfuric acid; (l) exhibit the characteristics of an oil which has been incompletely distilled after subjection to such sulfuric acid as attacks smoky hydrocarbons not attacked by 66° B. acid.

The figures given can be modified by varying the procedure, without exceeding the limits of the invention; and possibly some one or more of the characteristics mentioned might be absent from some of the resulting products. By mixing a product of the precise character stated with other oils, products can be obtained which do not have or exhibit all these properties or phenomena, but which yet are within the invention. The possession by the oil of the characteristics mentioned under (i) (k) and (l) would be obvious from the processes used in obtaining the same.

To show the characteristic (h) the oil may be distilled in a liter flask, such as ordinarily used in the laboratory for fractional distillations, and the distillate be collected in separate portions for each interval of 25° F., as indicated by a thermometer whose bulb is placed in the upright neck of the flask just below where the side tube is joined thereto. A sample of each distillate portion is then treated by agitation with fuming sulfuric acid and repetition of the operation (if necessary) until the acid, when drawn off, is found to fume. The percentage by which the volume of a given distillate portion has then been diminished is to be taken as the percentage therein before testing of hydrocarbons that quickly reduce fuming to non-fuming sulfuric acid. The fuming acid used should be 90 per cent. sulfuric monohydrate and 10 per cent. sulfuric anhydrid.

To show characteristic (g) a test distillation may be made and the portions coming over in 25° F. between 400° F. and 500° F. separately collected and tested for refractive index with the refractometer. The four numbers so obtained are then added together and divided by four to get the average refractive index of said portions.

To show characteristics (e) and (f) a test distillation may be made and the distillate portions coming over in 25° F. intervals collected separately. A measured amount of each distillate portion is dissolved in enough carbon disulfid to give a solution of five times the volume of dissolved distillate. A small quantity, say, 5 cc. (containing 1 cc. of distillate) of the said solution is placed in a dry stoppered bottle, which is wrapped in a piece of cloth to keep out the light. Five times the volume (25 cc.) of a decinormal solution of bromin in dry redistilled carbon disulfid is added; and the bottle, with its contents, after having been shaken, is set away in a dark place for fifteen minutes. Then a few cubic centimeters of potassium iodid solution and a little starch solution for indicator are added; the solution of bromin and oil is decolorized with a decinormal solution of sodium thiosulfate; and the volume required for the decoloration is noted. The subtrac-

tion of this volume from the volume of thiosulfate solution required to decolorize the same volume (25 cc. as above) of the bromin solution without the oil gives a measure from 5 which the percentage of bromin absorbed by the oil can be calculated. For simplicity of calculation, each cubic centimeter of said measure can be taken as indicating in every case one per cent. of bromin absorbed; and 10 no regard need be given to the difference in specific gravity of the portions of distillate coming over in different 25° F. intervals.

To show characteristic (d) a test distillation can be made and the distillate portions 15 coming over in 25° F. intervals above 400° F. collected separately. The distillate portions obtained can be tested with an hydrometer and the results averaged or compared severally with those obtained by similarly 20 testing distillate portions similarly obtained in the same temperature intervals from Pennsylvania petroleum, either directly from the crude Pennsylvania oil, or from either the burning oil distillate, or the finished burning oil derived in the usual way 25 from such crude.

To show characteristic (c) the oil can be distilled in a laboratory flask provided with a thermometer in the upright neck as afore- 30 said.

To show characteristic (b) the oil may be burned in an ordinary petroleum (kerosene) lamp. A good flame will show that the oil has the proper mobility; were it too 35 viscous, not enough oil would climb the wick to support the flame.

In my experience an oil with a refractive index of 1.4540 or 1.4545 will be non-smoking, while one with an index of 1.4600 will 40 be smoky, although substantially less so than oil of like boiling point obtained in the ordinary way from Beaumont petroleum. Probably one with an index of 1.4560 would pass as non-smoking; and one with even a 45 higher index might do so.

To show characteristic (a) the refractive index of the oil can be obtained by the refractometer in the known way and the result compared when necessary with that obtained similarly from oil of like boiling point obtained from Beaumont petroleum by the ordinary fractional distillation and treatment of distillate with 66° B. sulfuric acid.

55 Where two or more of the characteristics (h), (g), (f), (e), (d) and (c) are to be determined, one distillation would, of course, suffice, the amount distilled being sufficient to yield portions of distillate in the respective 25° F. intervals large enough for the tests to be made upon the same.

In carrying out the refining of Beaumont petroleum in accordance with the invention, instead of collecting as part of the cracked oil distillate the oil which comes over after

the first burning oil cut and before cracking begins, said oil could be collected in two portions, the first of which need not be distilled again before subjection to the 98% acid. According to this modification of the 70 described procedure, after the first burning oil cut had been collected in the receiver *d* as above described, the distillate would next be collected in the receiver *h* so long as the oil from the worm end should be sufficiently 75 deprived of smoky hydrocarbons by treatment with a moderate amount of 98% acid followed by an incomplete distillation, and then the rest of the distillate from the crude oil would be collected in receiver *g* (a 80 fourth receiver being provided for emergencies). The oil in receiver *g* would be distilled in still *k* and the distillate collected partly in the receiver *n* and partly in the receiver *p* as above described. The oils from 85 receivers *d* and *n* (separately or in admixture) would be treated with acid of 66° B., followed by incomplete distillation of the treated oil as before described for the first and second burning oil cuts. The oils from 90 receivers *h* and *p* (separately or in admixture) would be subjected to 98% acid, followed by incomplete distillation of the so-treated oil, as before described for the third 95 burning oil cut. Moreover, instead of treating the said third burning oil cut with 98% acid in the first instance, it could first be treated in whole or in part with 66° B. acid and then with 98% acid. Or before subjecting the said cut to the 98% acid, it 100 could in whole or in part be treated with acid intermediate 66° B. acid and 98%, with or without a preliminary treatment with 66° B. acid. In this way there might be a saving of acid.

In my experience 66° B. sulfuric acid can be used with beneficial effect on the oil to the extent of six to eight pounds thereof to the barrel of oil (40 gallons to the barrel). Also in my experience non-fuming acid of about one per cent. below 98% acid has done effective work when employed to the extent of about two-thirds of a pound thereof to the gallon of oil.

When employing (either or both) 66° 115 B. acid and intermediate acid in connection with 98% acid, it is considered best to select the third burning oil cut with reference to its capacity for satisfactory treatment with two pounds of 98% acid to the gallon of 120 oil as aforesaid, and then to use less than two pounds of 98% acid after the preliminary treatment or treatments with either or both the 66° B. and intermediate acids. If too much 66° B. or intermediate acid is not 125 used, an equal weight of 98% acid might be replaced thereby; and, according to my experience, the yield in quality and quantity of finished oil would be practically the same, as if neither 66° B. acid nor intermediate 130

acid, but only 98% acid, two pounds to the gallon of oil, should be used.

Instead of selecting the third burning oil cut with reference to its capacity for satisfactory treatment with 98% acid (two pounds to the gallon of oil), the selection could be made with reference to its capacity for treatment with such acid preceded by (either or both) 66° B. acid and intermediate acid in the desired relative amounts. Moreover, it will be understood that the amount of acid (whether 98% acid alone or 98% acid with either or both the 66° B. and intermediate acids) which is made the basis for selecting the third burning oil cut may be less than two pounds to the gallon of oil, or it may be more than said two pounds, so long as it is moderate in amount.

The finished oil in any of the foregoing cases should possess all of the before mentioned characteristics (a-l, both inclusive, as above). Nor would the possession of them by the finished oil in any case necessarily be affected by a partial replacement of 98% acid with fuming sulfuric acid containing less than about 98% monohydrate or by sulfuric anhydrid. This would be done by using of said fuming acid or anhydrid a weight about equal to the amount of 98% acid replaced thereby, and otherwise proceeding as above set forth. If an entire replacement should be made, the oil obtained would have all the specified characteristics except those due to subjection to 98% acid.

If it should be preferred to effect the removal of smoky hydrocarbons without the incomplete distillation after treatment with 98% acid or with the stronger fuming acid, this could be done, the acid being applied, say, in lots of two pounds to the gallon of oil until sufficient freedom from smoky hydrocarbons results and the procedure otherwise being as above set forth; and in such case the oil obtained would have all the specified characteristics except those due to said incomplete distillation. In case 98% acid should be also entirely replaced by the aforesaid stronger fuming acid, the finished oil would also lack the characteristics due to subjection to 98% acid.

If an oil which has the characteristic (h) should be mixed with Pennsylvania or Lima oil, the mixture might or might not show in the portions distilling over between 300° F. and 400° F. a larger percentage of hydrocarbons that quickly reduce fuming to non-fuming sulfuric acid than in the portions distilling over between 400° F. and 500° F. or 550° F.

If an oil having the characteristic (e) should be mixed with Pennsylvania or Lima oil, the mixture would (unless the latter oil should be in too large proportion) show a greater percentage of bromin-absorbing hydrocarbons in the portions distilling over

between 300° F. and 400° F. than in the portions distilling over between 400° F. and 500° F. or 550° F.; but the difference in percentage would be less than in the straight Beaumont product. In my product claims, therefore, which mention characteristic (e), I do not restrict myself to a difference of four or more per cent, but include a difference of one, two or three per cent as well. Similarly, I do not restrict my product claims which mention characteristic (d) in such sense that the respective distillate portions should be denser than those yielded by Pennsylvania petroleum in the same temperature intervals by five or more degrees Baumé, but I intend it to include cases where the difference may be only two, three or four degrees Baume.

Should it be desired for any reason to select a burning oil third cut or other burning oil distillate with reference to its treatment with a moderate amount of intermediate acid with or without 98% acid and with or without 66° B. acid, an assay could be made with the predetermined amount of such acid or acids and the collection of distillate stopped when oil from the worm end should attain the proper gravity for stopping as shown by the assay.

According to my experience, a greater amount of 66° B. acid than about 6 or 8 pounds to the barrel of oil accomplishes but little work in proportion to the quantity of acid used. Such acid, I believe, would not give a practical yield of oil with refractive index as low as 1.4600, however large an amount of it might be employed. Also, according to my experience, intermediate acid, if used for more than about two-thirds of a pound of acid to the gallon of oil, would be more expensive than the amount of 98% acid which would be replaced thereby. Non-fuming acid containing full 98% to 98½% monohydrate is considered the best acid to use, whether supplemented or not by (either or both) 66° B. acid and intermediate acid. The expression "98% acid" as herein employed is not restricted, however, to that containing full 98% or more of sulfuric monohydrate; but it includes acid containing about (although under) 98% monohydrate, and in particular it includes non-fuming sulfuric acid containing such an approximation to 98% of sulfuric monohydrate as to give a fair yield of oil with a refractive index as low as or lower than about 1.4540 or 1.4545, or even between this figure and 1.4600.

Should it be so desired, the acid from (either or both) the hydrogen sulfid from the Beaumont or analogous crude oil and the sulfur dioxid from the acid sludge can be used for treating Beaumont or analogous oil in the form of 66° B. acid, intermediate acid, or stronger fuming acid as well as in

the form of 98% acid; or it can be sold in any desired kind or degree of concentration, the acid for treating the Beaumont or analogous burning oil distillate being secured by purchase or in any proper way.

5 In the hereinafter written claims where the following expressions occur they have the following respective meanings, namely:

(a). The expression "such sulfuric acid 10 as will attack smoky hydrocarbons of Beaumont petroleum not attacked by 66° B. sulfuric acid" means primarily sulfuric acid of about or above 98% monohydrate (fuming as well as non-fuming), and secondarily other proper sulfuric acid, as fuming sulfuric acid containing less than about 98% monohydrate, or sulfuric anhydrid, or acid of suitable strength intermediate 60° B. and 98% acids. The use of any one of the acids 15 or using two or more in succession would be the use of acid within the expression.

(b). The expression "burning oil fraction of such petroleum" means primarily the hydrocarbons suitable for burning oil (kerosene) which can be obtained from Beaumont or analogous petroleum by distillation with the aid of cracking to increase the yield of the burning oil, and secondarily the hydrocarbons suitable for burning oil 25 (kerosene) which can be otherwise obtained from Beaumont or analogous petroleum, as, for example, by distillation without such cracking.

(c). The expression "separating the 30 lighter from the heavier portion of the smoky burning oil fraction of such petroleum" means primarily a separation in two distillations in one of which light uncracked hydrocarbons are obtained (as in the distillation of the crude oil, for example) and in the other of which light cracked hydrocarbons are obtained (as in the distillation of the cracked oil distillate, for example), the said burning oil fraction being obtained 35 from the Beaumont or analogous oil by distillation with the aid of cracking to increase the yield of burning oil. The expression also means a separation of the light hydrocarbons in other ways, as, for example, a separation of them in one or more distillations from the cracked oil distillate (if cracking to increase the yield of burning oil is resorted to) or from the crude or other uncracked oil (if resort to such cracking be 40 not had).

(d). The expression "the procedure being carried on in the specified manner for reducing the amount of acid employed" means that the procedure consists in part of some one, two or three or of all four of the 45 following operations which are severally and collectively calculated to diminish the ratio of acid consumed to yield of non-smoking or less smoky burning oil, namely, (1) separation of the lighter from the

heavier portion of the burning oil fraction for admixture after subjection of the said heavier portion by itself to such sulfuric acid as will attack smoky hydrocarbons of Beaumont petroleum not attacked by 66° B. 50 sulfuric acid, so that such acid is not consumed on the said lighter portion without corresponding increase in the said yield; (2) incomplete distillation of the lighter portion, after it has been subjected to ordinary concentrated sulfuric acid, whereby smoky hydrocarbons are left in the still whose removal otherwise might require more expensive acid; (3) collection of the burning oil fraction with reference to a satisfactory treatment thereof with a moderate amount of acid, since a larger volume of so collected distillate than of distillate as ordinarily heretofore collected can be made non-smoking or less smoky with a given amount 80 of acid; (4) incomplete distillation of the oil subjected to such sulfuric acid as will attack smoky hydrocarbons of Beaumont petroleum not attacked by 66° B. sulfuric acid; for smoky hydrocarbons are thereby 90 left in the still whose removal otherwise might require more acid.

In my divisional application No. 363,713, filed March 21, 1907, as a continuation of this present application and made in consequence of official requirement of division, I have described and claimed the apparatus herein disclosed, intending thereby to protect all and singular the new and useful parts, improvements and combinations embodied in said apparatus.

I claim as my invention or discovery:

1. In refining Beaumont or analogous petroleum, the improvement consisting in sub- 105 jecting the smoky burning oil fraction of such petroleum to the specified 98% sulfuric acid, substantially as described.

2. In refining Beaumont or analogous petroleum, the improvement consisting in sub- 110 jecting the smoky burning oil fraction of such petroleum to such sulfuric acid as will attack smoky hydrocarbons of Beaumont petroleum not attacked by 66° B. sulfuric acid, and incompletely distilling the so-treated fraction, substantially as described. 115

3. In refining Beaumont or analogous petroleum, the improvement consisting in collecting the burning oil fraction with reference to its capacity for satisfactory treatment with a moderate amount of appropriate acid, and subjecting the so-collected oil to a moderate amount of such sulfuric acid as will attack smoky hydrocarbons of Beaumont petroleum not attacked by 66° B. sulfuric acid, substantially as described. 120

4. In refining Beaumont or analogous petroleum, the improvement consisting in collecting the burning oil fraction with reference to its capacity for satisfactory treatment with a moderate amount of appropri- 125

ate acid, subjecting the so-collected oil to a moderate amount of such sulfuric acid as will attack smoky hydrocarbons of Beaumont petroleum not attacked by 66° B. sulfuric acid, and incompletely distilling the so-treated oil, substantially as described.

5. In refining Beaumont or analogous petroleum, the improvement consisting in separating the lighter from the heavier portion of 10 the smoky burning oil fraction of such petroleum, subjecting said heavier portion by itself to such sulfuric acid as will attack smoky hydrocarbons of Beaumont petroleum not attacked by 66° B. sulfuric acid, 15 and mixing the said lighter portion with the so-treated heavier portion, substantially as described.

6. In refining Beaumont or analogous petroleum, the improvement consisting in 20 separating the lighter from the heavier portion of the smoky burning oil fraction of such petroleum, subjecting said heavier portion by itself to such sulfuric acid as will attack smoky hydrocarbons of Beaumont petroleum not attacked by 66° B. sulfuric acid, 25 incompletely distilling the so-treated portion, and mixing the said lighter portion with the distillate from such incomplete distillation, substantially as described.

30 7. In refining Beaumont or analogous petroleum, the improvement consisting in separating the lighter from the heavier portion of the smoky burning oil fraction of such petroleum, collecting the said heavier portion with reference to its satisfactory 35 treatment with a moderate amount of appropriate acid, subjecting the so-collected heavier portion by itself to a moderate amount of such sulfuric acid as will attack smoky hydrocarbons of Beaumont petroleum not attacked by 66° B. sulfuric acid, 40 and mixing the said lighter portion with the so-treated heavier portion, substantially as described.

45 8. In refining Beaumont or analogous petroleum, the improvement consisting in separating the lighter from the heavier portion of the smoky burning oil fraction of such petroleum, collecting the said heavier portion with reference to its satisfactory 50 treatment with a moderate amount of appropriate acid, subjecting the so-collected heavier portion by itself to a moderate amount of such sulfuric acid as will attack smoky hydrocarbons of Beaumont petroleum not attacked by 66° B. sulfuric acid, 55 incompletely distilling the so-treated heavier portion, and mixing the said lighter portion with the distillate from such incomplete distillation, substantially as described.

60 9. In refining Beaumont or analogous petroleum, the improvement consisting in separating the lighter from the heavier portion of the smoky burning oil fraction of such petroleum, subjecting said lighter por-

tion to ordinary concentrated sulfuric acid, incompletely distilling the so-treated lighter portion, and mixing the distillate from such incomplete distillation with a heavier portion of said fraction from which smoky hydrocarbons have been separated, substantially as described.

10. In refining Beaumont or analogous petroleum, the improvement consisting in 75 separating the lighter from the heavier portion of the smoky burning oil fraction of such petroleum, subjecting said lighter portion to ordinary concentrated sulfuric acid, incompletely distilling the so-treated lighter portion, subjecting said heavier portion by itself to such sulfuric acid as will attack smoky hydrocarbons of Beaumont petroleum not attacked by 66° B. sulfuric acid, and mixing the distillate from the incomplete distillation of said lighter portion with 85 the so-treated heavier portion, substantially as described.

11. In refining Beaumont or analogous petroleum, the improvement consisting in separating the lighter from the heavier portion 90 of the smoky burning oil fraction of such petroleum, subjecting said lighter portion to ordinary concentrated sulfuric acid, incompletely distilling the so-treated lighter portion, subjecting said heavier portion by 95 itself to such sulfuric acid as will attack smoky hydrocarbons of Beaumont petroleum not attacked by 66° B. sulfuric acid, incompletely distilling the so-treated heavier portion, and mixing the distillates from the 100 two incomplete distillations, substantially as described.

12. In refining Beaumont or analogous petroleum, the improvement consisting in 105 separating the lighter from the heavier portion of the smoky burning oil fraction of such petroleum, subjecting said lighter portion to ordinary concentrated sulfuric acid, incompletely distilling the so-treated lighter portion, collecting the said heavier portion with reference to its satisfactory treatment with a moderate amount of appropriate acid, subjecting the so-collected heavier portion by itself to a moderate amount of such sulfuric acid as will attack smoky hydrocarbons of Beaumont petroleum not attacked by 66° B. sulfuric acid, and mixing the distillate from the incomplete distillation of said lighter portion with the so-treated heavier portion, substantially as described.

13. In refining Beaumont or analogous petroleum, the improvement consisting in separating the lighter from the heavier portion of the smoky burning oil fraction of 125 such petroleum, subjecting said lighter portion to ordinary concentrated sulfuric acid, incompletely distilling the so-treated lighter portion, collecting the said heavier portion with reference to its satisfactory treatment

- with a moderate amount of appropriate acid, subjecting the so-collected heavier portion by itself to a moderate amount of such sulfuric acid as will attack smoky hydrocarbons of Beaumont petroleum not attacked by 66° B. sulfuric acid, incompletely distilling the so-treated heavier portion, and mixing the distillates from the two incomplete distillations, substantially as described.
- 10 14. In refining Beaumont or analogous petroleum, the improvement consisting in obtaining burning oil distillate from such petroleum with the aid of cracking to increase the yield of burning oil, separating the lighter from the heavier portion of said distillate in two distillations in one of which light uncracked hydrocarbons and in the other of which light cracked hydrocarbons are obtained, and mixing both such sets of hydrocarbons with a heavier portion of the burning oil fraction of such petroleum from which smoky hydrocarbons have been separated, substantially as described.
- 15 15. In refining Beaumont or analogous petroleum, the improvement consisting in separating the lighter from the heavier portion of the smoky burning oil fraction of such petroleum, and in subjecting said heavier portion by itself to such sulfuric acid as will attack smoky hydrocarbons of Beaumont petroleum not attacked by 66° B. sulfuric acid, substantially as described.
- 20 16. In refining Beaumont or analogous petroleum, the improvement consisting in separating the lighter from the heavier portion of the smoky burning oil fraction of such petroleum, and in subjecting said heavier portion by itself to such sulfuric acid as will attack smoky hydrocarbons of Beaumont petroleum not attacked by 66° B. sulfuric acid, and in incompletely distilling the so treated oil, substantially as described.
- 25 17. In refining Beaumont or analogous petroleum, the improvement consisting in heating such petroleum to evolve hydrogen sulfid, converting it into such sulfuric acid as will attack smoky hydrocarbons of Beaumont petroleum not attacked by 66° B. sulfuric acid, and subjecting the smoky burning oil fraction of such petroleum to the so obtained acid, the procedure being carried on in the specified manner for reducing the amount of acid employed, substantially as described.
- 30 18. In refining Beaumont or analogous petroleum, the improvement consisting in subjecting the smoky burning oil fraction of such petroleum to such sulfuric acid as will attack smoky hydrocarbons of Beaumont petroleum not attacked by 66° B. sulfuric acid, converting the sulfur content of the resulting acid sludge into such acid as aforesaid, and subjecting oil of said fraction to the so-obtained acid, the procedure being carried on in the specified manner for di-
- minishing the amount of acid employed, substantially as described.
- 35 19. In refining Beaumont or analogous petroleum, the improvement consisting in distilling such petroleum to obtain burning oil distillate, subjecting gas evolved from the sulfur containing oil below about 500° F., more or less, to operations for converting its sulfur content into such sulfuric acid as will attack smoky hydrocarbons of Beaumont petroleum not attacked by 66° B. sulfuric acid, subjecting the so obtained burning oil distillate to such sulfuric acid as aforesaid obtained in part from said gas, converting the sulfur content of the resultant acid sludge into such sulfuric acid as aforesaid, and subjecting so obtained burning oil distillate to the so obtained acid, the procedure being carried on in the specified manner for diminishing the amount of acid employed, substantially as described.
- 40 20. A new or improved petroleum or hydrocarbon oil which has a refractive index less as specified than is possessed by oil of like boiling point obtained from Beaumont petroleum by the ordinary fractional distillation and treatment of distillate with 66° B. sulfuric acid; which has mobility proper for climbing a lamp wick; which distils within the temperature limits of 45° F. and 55° F. on a test distillation within temperature intervals of 25° F. portions of distillate which are, respectively, of greater gravity as specified than the portions similarly yielded in the same temperature intervals by Pennsylvania petroleum; and which is further distinguished by exhibiting the characteristics of an oil which has been subjected to 98% sulfuric acid, in contradistinction to oil of the same refractive index, mobility, volatility and gravity which has not been so treated; substantially as described.
- 45 21. A new or improved petroleum or hydrocarbon oil which has a refractive index less as specified than is possessed by oil of like boiling point obtained from Beaumont petroleum by the ordinary fractional distillation and treatment of distillate with 66° B. sulfuric acid; which has mobility proper for climbing a lamp wick; which distils within the temperature limits of 50° F. and 60° F. on a test distillation within temperature intervals of 25° F. portions of distillate which are, respectively, of greater gravity as specified than the portions similarly yielded in the same temperature intervals by Pennsylvania petroleum; and which is further distinguished by exhibiting the characteristics of an oil which has been incompletely distilled after subjection to such sulfuric acid as attacks smoky hydrocarbons of Beaumont petro-

leum not attacked by 66° B. acid, in contradistinction to oil of the same refractive index, mobility, volatility and gravity which has not been so treated and distilled; substantially as described.

22. A new or improved petroleum or hydrocarbon oil which has a refractive index less as specified than is possessed by oil of like boiling point obtained from Beaumont 10 petroleum by the ordinary fractional distillation and treatment of distillate with 66° B. sulfuric acid; which has mobility proper for climbing a lamp wick; which distils within the temperature limits of burning 15 oil (kerosene); which yields between 400° F. and 550° F. on a test distillation within temperature intervals of 25° F. portions of distillate which are, respectively, of greater gravity as specified than the portions similarly 20 yielded in the same temperature intervals by Pennsylvania petroleum; and which is further distinguished by having in the portions distilling over in 25° F. intervals between 300° F. and 400° F. amounts of hydrocarbons that quickly reduce fuming to non-fuming sulfuric acid, which amounts are larger than those in the portions distilling over in 25° F. intervals between 400° F. and 550° F.; and also by exhibiting in these 25 latter portions an average bromin-absorbing capacity which is less than six per cent. and also less as specified than that of the portions distilling over in 25° F. intervals between 300° F. and 400° F.; substantially as 30 described.

23. A new or improved petroleum or hydrocarbon oil which has a refractive index less than 1.4600; which has mobility proper for climbing a lamp wick; which distils 40 within the temperature limits of burning oil (kerosene); which yields between 400° F. and 500° F. on a test distillation within temperature intervals of 25° F. portions of distillate whose densities average not heavier 45 than about 34 $\frac{1}{2}$ ° B. nor lighter than about 40° B.; and which is further distinguished by having in the portions distilling over in 25° F. intervals between 300° F. and 400° F. amounts of hydrocarbons that 50 quickly reduce fuming to non-fuming sulfuric acid, which amounts are larger than those in the portions distilling over in 25° F. intervals between 400° F. and 550° F.; and also by exhibiting in these latter portions an average bromin-absorbing capacity 55 which is less than six per cent. and also less as specified than that of the portions distilling over in 25° F. intervals between 300° F. and 400° F.; substantially as described.

24. A new or improved petroleum or hydrocarbon oil which has a refractive index less than 1.4600; which has mobility proper for climbing a lamp wick; which distils 60 within the temperature limits of burning oil (kerosene); which yields between 400° F. and 65

F. and 500° F. on a test distillation within temperature intervals of 25° F. portions of distillate whose densities average not heavier than about 34 $\frac{1}{2}$ ° B. nor lighter than about 40° B.; and which is further distinguished 70 by exhibiting characteristics of an oil which has been subjected to 98% sulfuric acid, in contradistinction to oil of the same refractive index, mobility, volatility and gravity which has not been so treated; substantially 75 as described.

25. A new or improved petroleum or hydrocarbon oil which has a refractive index less than 1.4600; which has mobility proper for climbing a lamp wick; which distils 80 within the temperature limits of burning oil (kerosene); which yields between 400° F. and 500° F. on a test distillation within temperature intervals of 25° F. portions of distillate whose densities average not heavier 85 than about 34 $\frac{1}{2}$ ° B. nor lighter than about 40° B.; and which is further distinguished by exhibiting the characteristics of an oil which has been incompletely distilled after 90 subjection to such sulfuric acid as attacks smoky hydrocarbons of Beaumont petroleum not attacked by 66° B. acid, in contradistinction to oil of the same refractive index, mobility, volatility and gravity which has not been so treated and distilled; substantially 95 as described.

26. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average not heavier 100 than about 34 $\frac{1}{2}$ ° B. nor lighter than about 40° B., whose refractive indexes average not more than 1.4620 plus twenty or minus fifteen ten-thousandths for each degree B. the average density is heavier or lighter than 105 35° B., and whose characteristics in general 110 are those due to a subjection to 98% sulfuric acid, in contradistinction to oil of the same refractive index, mobility, volatility and gravity which has not been so treated; substantially as described. 115

27. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average not heavier 120 than about 34 $\frac{1}{2}$ ° B. nor lighter than about 40° B., whose refractive indexes average not more than 1.4620 plus twenty or minus fifteen ten-thousandths for each degree B. the average density is heavier or lighter than 35° B., and whose characteristics in general 125 are those due to an incomplete distillation 130

after subjection to such sulfuric acid as attacks smoky hydrocarbons of Beaumont petroleum not attacked by 66° B. acid, in contradistinction to oil of the same refractive index, mobility, volatility and gravity which has not been so treated and distilled; substantially as described.

28. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average not heavier than about 34 $\frac{1}{2}$ ° B. nor lighter than about 40° B., whose refractive indexes average not more than 1.4620 plus twenty or minus fifteen ten-thousandths for each degree B. the average density is heavier or lighter than 35° B., whose contents of hydrocarbons that readily reduce fuming to non-fuming sulfuric acid average less than the contents of the portions distilling over in 25° F. intervals between 300° F. and 400° F., and whose bromin-absorbing capacities average less than six per cent. and also less as specified than those of the portions distilling over in 25° F. intervals between 300° F. and 400° F.; substantially as described.

29. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average between about 34 $\frac{1}{2}$ ° B. and 36° B., and whose refractive indexes average not more than 1.4610 with an allowance at the rate of plus forty ten-thousandths for each degree B. the average density is heavier or minus twenty for each

degree B. it is lighter than 35° B.; substantially as described.

30. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average between about 34 $\frac{1}{2}$ ° B. and 36° B., whose bromin-absorbing capacities average less than six per cent., and whose refractive indexes average not more than 1.4610 with an allowance at the rate of plus forty ten-thousandths for each degree B. the average density is heavier or minus twenty for each degree B. it is lighter than 35° B.; substantially as described.

31. In refining Beaumont or analogous petroleum, the improvement consisting in subjecting the smoky burning oil fraction of such petroleum to such non-fuming sulfuric acid as will attack smoky hydrocarbons of Beaumont petroleum not attacked by 66° B. sulfuric acid; substantially as described.

32. In refining Beaumont or analogous petroleum, the improvement consisting in subjecting the smoky burning oil fraction of such petroleum first to sulfuric acid intermediate 66° B. sulfuric acid and the specified 98% sulfuric acid and afterward to such sulfuric acid as will attack smoky hydrocarbons of Beaumont petroleum not attacked by the said intermediate acid; substantially as described.

In testimony whereof I have signed my name to this specification in the presence of two subscribing witnesses.

CLARENCE I. ROBINSON.

J. E. EGGLESTON,
A. P. ARNOLD.

Corrections in Letters Patent No. 968,692.

It is hereby certified that in Letters Patent No. 968,692, granted August 30, 1910, upon the application of Clarence I. Robinson, of West New Brighton, New York, for an improvement in "Refining Petroleum," errors appear in the printed specification requiring corrections as follows: Page 4, line 14, the word "sulfate" should read *sulfid*; page 13, lines 73-74, the word "convertings" should read *converting*; and that the said Letters Patent should be read with these corrections therein that the same may conform to the record of the case in the Patent Office.

Signed and sealed this 10th day of January, A. D., 1911.

[SEAL.]

C. C. BILLINGS,

Acting Commissioner of Patents.

after subjection to such sulfuric acid as attacks smoky hydrocarbons of Beaumont petroleum not attacked by 66° B. acid, in contradistinction to oil of the same refractive index, mobility, volatility and gravity which has not been so treated and distilled; substantially as described.

28. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average not heavier than about 34 $\frac{1}{2}$ ° B. nor lighter than about 40° B., whose refractive indexes average not more than 1.4620 plus twenty or minus fifteen ten-thousandths for each degree B. the average density is heavier or lighter than 35° B., whose contents of hydrocarbons that readily reduce fuming to non-fuming sulfuric acid average less than the contents of the portions distilling over in 25° F. intervals between 300° F. and 400° F., and whose bromin-absorbing capacities average less than six per cent. and also less as specified than those of the portions distilling over in 25° F. intervals between 300° F. and 400° F.; substantially as described.

29. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average between about 34 $\frac{1}{2}$ ° B. and 36° B., and whose refractive indexes average not more than 1.4610 with an allowance at the rate of plus forty ten-thousandths for each degree B. the average density is heavier or minus twenty for each

degree B. it is lighter than 35° B.; substantially as described.

30. A new or improved petroleum or hydrocarbon oil having mobility proper for climbing a lamp wick; distilling within the temperature limits of burning oil (kerosene); and yielding between 400° F. and 500° F. on a test distillation within temperature intervals of 25° F. portions of distillate whose densities average between about 34 $\frac{1}{2}$ ° B. and 36° B., whose bromin-absorbing capacities average less than six per cent., and whose refractive indexes average not more than 1.4610 with an allowance at the rate of plus forty ten-thousandths for each degree B. the average density is heavier or minus twenty for each degree B. it is lighter than 35° B.; substantially as described.

31. In refining Beaumont or analogous petroleum, the improvement consisting in subjecting the smoky burning oil fraction of such petroleum to such non-fuming sulfuric acid as will attack smoky hydrocarbons of Beaumont petroleum not attacked by 66° B. sulfuric acid; substantially as described.

32. In refining Beaumont or analogous petroleum, the improvement consisting in subjecting the smoky burning oil fraction of such petroleum first to sulfuric acid intermediate 66° B. sulfuric acid and the specified 98% sulfuric acid and afterward to such sulfuric acid as will attack smoky hydrocarbons of Beaumont petroleum not attacked by the said intermediate acid; substantially as described.

In testimony whereof I have signed my name to this specification in the presence of two subscribing witnesses.
